UNITED STATES PATENT OFFICE.

LEAH KUHN, OF SPOKANE, WASHINGTON.

PORTABLE TOILET FOR INFANTS.

Application filed April 15, 1924. Serial No. 706,634.

An object of this invention is to provide a portable toilet for infants that is small, neat, and quickly encased so that it can be transported from place to place; and which 5 can also be easily and quickly removed from the case and made ready for use.

An object of the invention is to provide a portable toilet that can be arranged for transportation so that it presents a pleasing 10 appearance, and also so that the nature of the appliance is fully obscured.

Other objects, advantages and features of invention may appear from the accompanying drawing, the subjoined detailed description 15 and the appended claim.

The accompanying drawing illustrates the invention.

Figure 1 is a perspective view of the appliance enclosed in a casing ready for transportation. 20

Fig. 2 is an enlarged central longitudinal section through the casing enclosed appliance as it is arranged for transportation.

Fig. 3 is a front view of the appliance 25 constructed in accordance with this invention and showing the back in folded position.

Fig. 4 is an enlarged plan view of the appliance with the back unfolded.

30 Fig. 5 is a central longitudinal section on line $\alpha\beta$, Figs. 3, 4 with the back in unfolded position and the appliance ready for use.

Fig. 6 is a perspective view of the false drawer detached from the appliance.

35 Fig. 7 is a perspective view of the appliance on a small scale showing the back in unfolded position and the false drawer partly removed.

The appliance comprises a base 1 to which 40 is attached by any well known means a back wall 2 and side walls 3; and the side walls 3 at their front edge are connected by a cross bar 4, so that a substantial front opening is provided that is normally closed by a false drawer 5.

45 The false drawer 5 comprises a front plate 6 to which is secured the sides 7 which are secured together at their upper rear corners by a cross bar 8; and the drawer is preferably provided with a finger grip 9 to facilitate removing it when desired.

Secured to the top of the back 2, side walls 3 and bar 4, is a toilet seat 10 that is provided with a centrally arranged opening 11 that is normally closed by the back rest 55 12 that is secured to the back wall 2 by the countersunk hinges 13 so that when desired the back rest can be removed to the open position shown in Figs. 4, 5 and 7.

Preferably the back rest 12 is slightly 60 longer than the seat 10 so that an edge portion 14 extends over the front edge of seat 10 as shown in Fig. 2 so as to form a finger hold to facilitate moving the back rest to open position. 65

A stop 15 is secured to the back 2 for limiting the movement of the back rest 12 from closed to open position; and preferably the top edge of the stop 15 is beveled as at 16 so as to permit the back rest 12 to incline 70 away from the seat 10 and out of alignment with the back wall 2 so as to form a comfortable back rest and seat.

By the foregoing construction and arrangement of parts an appliance is provided 75 with a compartment 17 into which can be inserted a usual toilet receptacle 18 that can be placed in or removed from the appliance removing and reinserting the false drawer 5.

The appliance may be made conveniently portable by a casing 19 as illustrated in Figs. 1 and 2 that can be formed of any desired material such as imitation leather that can be constructed into a neat slightly casing 80 85 as shown so that when the appliance is enclosed therein it will be completely obscured and a handle 20 is suitably attached to a top or cover 21.

I claim:

The portable toilet for infants set forth comprising a toilet seat; supporting walls for said seat said walls arranged to form a compartment under said seat; a false drawer closing an opening into the compartment 95 between said walls; a hinged back rest to said seat; and means for enclosing and transporting said toilet for infants.

In testimony whereof, I have hereunto set my hand at Los Angeles, California, this 100 8th day of April, 1924.

LEAH KUHN.
